US00D875404S

(12) **United States Design Patent** (10) Patent No.: **US D875,404 S**
(45) Date of Patent: **** Feb. 18, 2020**

(54) **DENTAL APPLIANCE**(71) Applicant: **Dyson Technology Limited**, Wiltshire (GB)(72) Inventors: **Stephen Benjamin Courtney**, Bath (GB); **Timothy Nicholas Stickney**, Gloucester (GB); **Thomas James Dunning Follows**, Swindon (GB); **William John Bex-Russell**, London (GB)(73) Assignee: **Dyson Technology Limited**, Malmesbury, Wiltshire (GB)(**) Term: **15 Years**(21) Appl. No.: **29/692,505**(22) Filed: **May 24, 2019****Related U.S. Application Data**

(62) Division of application No. 29/602,377, filed on May 1, 2017, now Pat. No. Des. 854,329.

(30) Foreign Application Priority Data

Nov. 2, 2016 (GB) 6002227
Nov. 2, 2016 (GB) 6002232
Nov. 2, 2016 (GB) 6002237

(51) LOC (12) Cl. **28-03**

(52) U.S. Cl.

USPC ..... **D4/101****(58) Field of Classification Search**

USPC D4/100, 101, 102, 104, 105, 106, 107, D4/108, 109, 110, 111, 112, 113, 114, D4/115, 116, 117, 118, 119, 120, 121, D4/122, 123, 124, 125, 126, 127, 128, D4/129, 130, 132, 133, 134, 136, 138, D4/199; D24/111, 127, 152, 177

CPC A46B 11/0062; A46B 13/04; A46B 2200/1066; A46B 11/00; A46B 13/00; A46B 15/0097

See application file for complete search history.

(57) CLAIM

We claim the ornamental design for a dental appliance, as shown and described.

DESCRIPTION

FIG. 1 is a perspective view of a dental appliance showing our new design;

FIG. 2 is a front elevation view thereof;

FIG. 3 is a rear elevation view thereof;

FIG. 4 is a side elevation view thereof;

FIG. 5 is a side elevation view of the opposite side of the design as that shown in FIG. 4;

FIG. 6 is a top plan view thereof; and,

FIG. 7 is a bottom plan view thereof.

The broken lines shown in the drawings illustrate portions of a dental appliance that form no part of the claimed design.
